2,623,579

INTERNAL FIRED GAS BURNER

Ernst A. Furkert, Chicago, Ill.; Annette Furkert
executrix of said Ernst A. Furkert, deceased

Application November 5, 1947, Serial No. 784,189

6 Claims. (Cl. 158—99)

1

This invention relates to improvements in fuel burner structures.

In flame hardening apparatus employing gaseous fuel, and in other types of heat treating apparatus, burners or nozzles are provided for directing the flames of hot combustion products upon the article to be heated. The gas employed may of course be one that provides a high flame temperature but in many heat treating installations the gas employed is a mixture of air and so-called city gas (either natural or manufactured or a mixture of the two), the gas and air being mixed by means of a gas mixing machine and delivered thereby to the burner or burners.

Burners for use in connection with such heating apparatus have been developed and used and generally are formed principally of ceramic or other high heat resistant material. Since the fuel mixture (air and gas) frequently is delivered to the burners at a relatively high velocity for the purpose of effecting high temperatures through rapid combustion of the fuel, it has been thought desirable by some to provide the burners with constricted flame outlets for insuring complete combustion of the fuel within the burners. The constriction of a burner outlet tends to build up back pressure of the gas within the burner chamber, thereby reducing, to some extent, the fuel burning capacity of the burner and promoting "blow-backs" into the duct that delivers the fuel to the burner.

It is an object of the present invention to provide an improved burner structure which avoids the employment of a constriction at the burner outlet, and which is adapted to insure substantially unimpeded flow of fuel through the burner whereby a maximum quantity of gas can be consumed in a unit of time for producing relatively high temperatures and whereby "blow-backs" are eliminated or greatly reduced.

A further object of the invention is to provide an improved burner of the type referred to which, while admitting the relatively unimpeded flow of fuel through the burner, aids in the ignition and complete combustion of the fuel within the burner chamber.

Another object of the invention is to provide a fuel burner structure comprising a pair of complementary refractory ceramic or "brick" members that define a combustion chamber and a holder for the "bricks" which retains them in proper cooperating relation while in use but permits the same to be removed readily for replacement or for substitution of a pair of bricks that provide a flame outlet having a shape particularly suitable for the heating purpose at hand.

2

Other objects of the invention relate to various features of construction and arrangement of parts which will be apparent from a consideration of the following specification and accompanying drawings wherein:

Fig. 1 is a sectional view taken on line 1—1 of Fig. 2 illustrating a burner assembly comprising an improved burner that is illustrative of the present invention and a burner shell thereon;

Fig. 2 is a front elevational view of the burner shown in Fig. 1;

Fig. 3 is a sectional view taken on line 3—3 of Fig. 1;

Fig. 4 is a sectional view, taken on line 4—4 of Fig. 5, illustrating a pair of complementary refractory sections or bricks of the form shown in the preceding figures;

Fig. 5 is a front elevation of the two refractory sections shown in Fig. 4;

Fig. 6 is a sectional view, taken on line 6—6 of Fig. 7 illustrating a pair of refractory sections of modified form;

Fig. 7 is a front elevational view of the sections shown in Fig. 6;

Fig. 8 is a top plan view of the sections shown in Fig. 6;

Fig. 9 is a sectional view taken on line 9—9 of Fig. 10;

Fig. 10 illustrates refractory sections of a second modified form;

Fig. 11 is a top plan view of a group of burners arranged in annular form about a gear to be heated.

Gaseous fuel burner structures of the type forming the subject matter of the present invention are adapted for use in brazing or hard soldering, in flame hardening operations and other industrial uses. In flame hardening operations for circular or annular articles such as gears, cams or the like where it is desirable that

only certain surface portions of the articles be heated to a hardening temperature, the application of heat rapidly to the portions to be hardened is necessary in order that the remaining portions will not be heated to a hardening temperature and it is desirable that the temperature of the parts that are not to be hardened be kept sufficiently low so as to avoid warpage of the article upon quenching. Thus in hardening gears, for example, it usually is desirable to harden only the working faces and roots of the teeth while leaving the gear body in an unhardened but tough condition that will be an assurance against breakage in use and which permits

the performance thereon of subsequent machine operations such as milling, turning or boring for

example. In rapidly heating such desired portions to the proper hardening temperature for quenching, where a relatively low flame temperature fuel, such as a mixture of air and city or any convenient gas, is used, it is desirable to train the flames or hot products of combustion quite precisely upon the parts of the article to be hardened while avoiding direct application of the heat to other parts of the article. It is likewise desirable to place the burner outlets quite close to the surface to be hardened for minimizing the entrainment of air by the burner blast and the resultant cooling action thereby produced.

In so arranging the burners about a circular or annular article, such as a gear for example, it is desirable generally that the burners be capable of being spaced closely together with their outlet ends disposed in close proximity to the surface to be hardened, the article being rotatable during the heating operation, or the burners being carried by a rotary structure for rotation about the stationary articles, as disclosed in U. S. Patent No. 2,407,230 granted September 10, 1946.

For the purpose of accomplishing the results mentioned and others that will be apparent to those skilled in the art, the burners 10 shown in the accompanying drawings for illustrative purposes preferably are of frusto pyramidal form which, when occasion requires, enables a plurality of the burners to be arranged closely about an annular article, such as a gear 11 shown in Fig. 11, for concentrating the hot combustion products or flames upon the teeth thereof as the gear rotates or as the burners are rotated about the gear or analogous article to be hardened.

The means for supporting the individual burners enabling the adjustment thereof to desired positions, or for rotating the same if they are rotatably mounted may be of any approved construction, such as is shown in my patent above mentioned. However, the burner structures herein shown comprise a pair of refractory ceramic members or bricks of complementary form providing a frusto pyramidal burner body 12 that is adapted to be seated within a supporting shell 13 shown in Fig. 1. The shells employed in a particular installation are of similar shape and are capable of being closely grouped about the gear 11 as indicated in Fig. 11. It will be understood that Fig. 11 illustrates one particular arrangement of a group of the improved burners and that in many instances of use they will not be in the arrangement shown, but may be spaced apart and staggered in different planes or turned at various angles as the exigencies of a particular heating job may require.

The brick sections shown in Figs. 1 to 5 inclusive are indicated by numerals 14 and 15, the sections meeting in a medial plane indicated at 16. The meeting faces of the sections 14 and 15 have complementary channels 17 and 18, respectively, therein that provide a combustion chamber indicated generally by the numeral 19. As shown in Figs. 4 and 5, the chamber 19 has a fuel inlet portion 20, and an outlet or nozzle portion 21, the axis of one being offset from the axis of the other, and the two chamber portions being united by an oblique portion 22 when the sections are in assembled relation.

The cross sectional shape of the combustion chamber 19, taken on any plane normal thereto, is square, the opposed walls of the respective

sections being parallel. The combustion chamber thus has no constriction that tends to obstruct the flow of fuel or products of combustion through it. The gaseous fuel that enters the inlet section 20 and is ignited therein, strikes the oblique wall 23, of the section 14, which produces turbulence of the gas stream for insuring more complete combustion within the chamber. The wall 23 and adjacent portions of the ceramic also becomes incandescent which further promotes combustion within the chamber.

The sections 14 and 15 of the ceramic can be cast or molded readily without the use of sand or other removable cores and can be assembled readily in pairs and inserted in the casings 13 of the burner structure.

The burner structure shown for illustrative purposes comprises a nut 25 that is mounted on a threaded end of a nipple 26, the nut being provided with a pair of radially extending pins 27 which enter openings 28 provided in rearwardly extending flanges 29 of the casing. By rotating the burner structure in a direction to release the ceramic sections from contact with the forwarded end of the nipple 26 the casing and the ceramic sections can be shifted axially of the pins to release one flange of the casing from the respective pin and then shifted in the other direction to free the other flange. The refractory sections can then be removed from the rear or large end of the casing and replacement sections substituted therefore, and by reversing the above described operations, the burner structure can be reassembled upon the pins and rotated to cause the nut 25 to draw the assembly rearwardly, causing the end of the duct to abut both ceramic sections for forcing them, relatively, forward in the casing which in turn, forces the meeting faces of the sections closely together.

In a burner assembly of the type shown in Fig. 1, provision may be made in the casing 30 to which gaseous fuel is delivered, as by a flexible duct 31 for the maintenance of a suitable pilot or igniting flame in the intake portion 20 of the combustion chamber 19 that constantly ignites the main gaseous fuel stream entering the chamber, such piloting arrangement not being shown herein. In Figs. 6, 7 and 8, the complementary ceramic sections 32 and 33 provide a combustion chamber 34 which varies in cross sectional dimensions but does not decrease in total area from entrance to outlet and hence avoids constricting the flow of gas or products of combustion through the chamber. It will be seen that the combustion chamber mentioned has an intake portion 35 that is square in cross section and an outlet or discharge portion 36 that is rectangular, being greater in the horizontal dimension as shown than in the vertical, although the burner may be used in positions different from that shown. The oblique chamber portion 37 connects the intake and outlet portions 34 and 35 to provide a wall 38 that produces turbulence and becomes incandescent as in the above described form of the brick members. The relative vertical dimensions of portion 37 of the chamber decrease progressively in a forward direction but the transverse dimensions of the chamber increase progressively to avoid reduction in cross sectional area. Thus in Fig. 6 the oblique section is shown as having converging upper and lower walls but in Fig. 8 it appears that the other walls flare outwardly. This relative change in dimensions, as noted, avoids the reduction in the fuel carrying capacity of the oblique chamber

portion but it does induce additional turbulence in the gas stream. The cross sectional area of the outlet portion 36 of the combustion chamber is not less than the cross-sectional area of portion 37 but it provides a discharge orifice that is narrow in one direction and relatively long in the other. For example, the longer dimension may correspond with the length of the teeth of gears to be hardened in which case the burner may be used in a position rotated 90° from the position shown in Fig. 7 or the narrow dimension may correspond to the width of an annular cam surface to be hardened in which case the burner may be used in the relative position shown in said 7.

The exterior dimensions of the sections of the ceramic shown in Figs. 6 to 8 enable them to be inserted in a casing 13 as described above with reference to the form shown in Fig. 1.

A third illustrative form of ceramic is shown in Figs. 9 and 10 comprising mating sections 39 and 40 which provide a combustion chamber 41, comprising three portions, i. e., the intake portion 42, the outlet portion 43, and the connecting oblique portion 44. The cross sectional shape of each portion is circular and the portions are designed to avoid diminution in gas carrying capacity from intake to outlet end. Oblique portion 44 provides a wall 45 against which the incoming gases impinge and which becomes incandescent as in the above described forms.

In the several forms of the burners illustrated, each is formed of two mating refractory sections that provide an oblique wall against which the burning gases impinge to produce incandescence and which cause turbulence in the flow of gaseous fuel through the combustion chamber for promoting combustion within the chamber. The two-part ceramic is preferred by reason of the simplicity of the operations required in molding the same although ceramics of one piece construction may be employed in attaining some of the advantages of the improved structure.

I claim:

1. A gas burner comprising a pair of mating refractory sections adapted to be assembled in face to face contact and having complementary formations in said faces providing a gas receiving and combustion passage extending from end to end of the assembled sections, said sections having exterior walls providing the assembly with a frusto-pyramidal shape, a casing for the sections provided with an interior surface of frusto-pyramidal form for engaging the exterior walls of said assembled sections for pressing the latter in face-to-face contact as the sections are moved forwardly in the casing with the exterior walls of the sections contacting the interior walls of the casing, an internally threaded member attached to the rear of said casing aligned with the adjacent end of the gas passage, and a threaded gas duct adapted to be screwed into said threaded member into contact with said refractory sections adjacent said end of the gas passage for forcing the refractory sections forwardly within the casing and effecting close face-to-face contact of said refractory sections.

2. A burner structure comprising in combination a burner having a body of refractory material provided with a combustion passage extending therethrough and within which gaseous fuel products are introduced at one end for combustion during progress through the passage, a shell on the exterior of the body, a threaded member removably attached to the rear of said

shell in registration with the intake of said passage, and a threaded gas duct engaged by said threaded member and abutting the adjacent end of said refractory body in registration with said intake for delivering gaseous fuel constituents directly into said passage and retaining the body in position within the shell.

3. A burner structure comprising in combination a burner having a body decreasing in transverse dimensions from the rear to the forward end and formed of two contacting portions, said body being provided with a fuel passage extending from end to end for receiving gaseous fuel constituents for combustion within the passage, said passage being formed in the contacting surfaces of the body portions, a shell complementarily shaped with respect to the exterior of the body for forcing said surfaces of the sections together as the body is moved forwardly into seating relation within the shell, a threaded member removably attached to the rear portion of said shell, and a threaded duct engageable by said threaded member and positionable thereby in registration with the intake end of said passage for delivering gaseous fuel constituents into said passage and cooperable with said threaded member for exerting pressure on both said body sections for pressing the same forwardly into seating position within said shell.

4. A gaseous fuel burner comprising a refractory brick-like body provided with a passage therethrough comprising an intake end portion for entrance of gaseous fuel constituents, an outlet end portion parallel with and axially offset from said intake portion, and an oblique intermediate portion connecting the intake and outlet portions and providing a wall oblique to the direction of flow of gases in the intake portion and against which the gaseous constituents impinge to promote intimate mixing thereof, said portions of said passage being of different cross-sectional shape and dimensioned to provide said passage with equivalent cross-sectional areas throughout the length thereof.

5. A gaseous fuel burner comprising a brick of refractory material provided with a combustion passage extending therethrough from end to end, said passage comprising a fuel intake portion, an outlet portion parallel with and offset axially from said intake portion and of different cross-sectional dimensions but of equal cross-sectional area, and an intermediate portion obliquely disposed between and in communication with the adjacent ends of said intake and outlet portions and shaped at the ends thereof in correspondence with the respective communicating ends of the other portions of the passage.

6. A gas burner comprising in combination a burner body comprising a pair of refractory members assembled in face-to-face relation and provided with complementary formations in said faces forming a gas receiving and gas combustion passage extending from end to end of the body, opposed exterior walls of the body being convergent in a forward direction, a casing open at the forward end and provided with side walls which converge forwardly and with which the convergent walls of the body contact and which force the contacting faces of the refractory members into close relation as the members are pressed forwardly into seating engagement within the casing, an internally threaded member attached to the rear of said casing axially aligned with the adjacent end of the

gas receiving passage in the body, and a threaded gas supply duct threaded into said threaded member at the rear of said casing and engaging both said refractory members in registration with the adjacent end of the gas passage for pressing the refractory members forwardly of the casing for effecting contact of the outer convergent walls of the body with the convergent walls of the casing for forcing the refractory members in close face-to-face contact and retaining the same in said position within the casing.
